PNEUMATIC HYDRAULIC PUMPING APPARATUS

Samuel V. Smith, Long Beach, Calif., assignor to Pneu-Hy Co., Long Beach, Calif., a corporation of California

Filed Aug. 19, 1957, Ser. No. 678,807

10 Claims. (Cl. 60—52)

This invention relates generally to apparatus used for pumping wells, and more particularly has to do with improvements in fluid pressure powered pump jacks operable to raise and lower well pump rods and the like.

In general fluid pressurized pump jacking units presently in use are characterized as regards their construction in relation to the well head as extending to a considerable height above the ground and over the well, it being conventional practice to mount a large pumping assembly vertically over the pump rod for supporting the latter and for reciprocating it up and down. However, at the present time there is increasing public and civic expression of a need for restricting the observable size of such equipment, particularly in residential areas where the benefits of petroleum production are recognized and sought after at the expense of accommodating to the necessary presence of the production machinery.

Accordingly, it is a major object of the present invention to substantially improve the construction and especially the arrangement of well pump jacking units so as to minimize the apparent size thereof to the observer, while at the same time increasing the reliability and improving the operation of the equipment. To this end, the invention contemplates the provision of apparatus for vertically reciprocating a well pump rod or the like projecting above ground surface level, comprising a plurality of vertical cylinders spaced apart laterally so that they may be sunk downwardly into the ground in laterally offset relation to the well, together with pistons reciprocable up and down in the cylinders and means for supporting the pump rod at its projection above ground by the pistons and for reciprocating the supported rod up and down in response to piston reciprocation. The pistons are then reciprocable below ground surface level by application of fluid pressure to them in the manner to be explained, so that a large part of the equipment needed to lift and lower the pump rod is underground and out of sight of the observer. Also, there is a minimum of jacking equipment over the well head itself, facilitating ready access to the well for servicing purposes. The ground surface level referred to will be understood to mean the surface immediately around the well head, so that the "surface" may comprise the bottom of a shallow open pit into which all of the equipment is received.

In the carrying out of the invention to suit the purpose described, the pistons and cylinders are preferably laterally spaced on opposite sides of a center corresponding to the well location, so that an above ground cross head structure interconnecting the piston rods may bridge over the well pump rod for reciprocating the latter as the pistons are displaced up and down in the cylinders. Such displacement is effected by means intermittently communicating hydraulic pressure, for example, to a first pair of jacking pistons on opposite sides of the well and tending intermittently to raise the pump rod, and also by means constantly communicating gas pressure to a second pair of balance pistons likewise spaced on opposite sides of the well and underground, tending constantly to raise the

2

pump rod. When, as contemplated, the pressure communicated to the balance pistons is insufficient alone to raise the pump rod, the latter is lifted only during communication of hydraulic pressure to the jacking pistons, interruption of such communication allowing the pistons to drop on the pump rod downstroke, the rate of drop being controlled by restricting the backflow of hydraulic fluid pushed from the cylinders by the pistons, as will be explained.

- 10 Another major object of the invention concerns the provision of valve means responsive to reciprocation of the pistons for controlling interruption of hydraulic fluid pressure communication to the pistons, the valve placing pump discharged hydraulic fluid in communication with the jacking pistons on the pump rod upstroke, and placing fluid backflow therefrom in communication with the pump intake during the pump rod downstroke, the net effect of the latter being to brake and thereby control the dropping rate of the pump rod. At this time, the 15 pump discharge is placed in communication with the balance pistons so that the pump then discharges against the gas pressure constantly communicated to the balance pistons.

Other additional objects of the invention include the 20 provision of means for maintaining a predetermined pressure differential between the pressure exerted on the hydraulic fluid by the jacking pistons under the weight of the pump rod load, and the gas pressure communicated from a gas reservoir to the balance pistons via hydraulic liquid, so that as the load increases or decreases, the balance pressure may likewise increase or decrease to balance the load and thereby permit the hydraulic fluid pump to operate for effectively lifting the pump rod in the well.

25 30 35 These and other features and objects of the invention, as well as the details of an illustrative embodiment, will be more fully understood from the following detailed description of the drawings, in which:

Fig. 1 is a general view showing in elevation the pumping apparatus and its relation to the well head;

Fig. 2 is a plan view of the Fig. 1 apparatus;

Fig. 3 is an enlarged vertical section taken through actuating mechanism for the pilot valve;

Fig. 4 is an enlarged view taken in section through 40 a part of the Fig. 3 mechanism, the pilot valve and master valve, showing how these operate with relation to one another;

Fig. 5 is a partial plan view of Fig. 1 showing mechanism used to regulate the gas pressure in a reservoir;

50 Fig. 6 is a section taken through actuating mechanism used for comparing reservoir gas pressure exerted on the balance pistons and hydraulic fluid pressure exerted on the jacking pistons; and

Fig. 7 is a section taken through the lower portion 55 of the gas reservoir illustrating the manner in which system fluid is cooled.

Referring to the apparatus as shown in Figs. 1 and 2 and generally indicated at 10, the latter includes a pair of balance cylinders 11 extending vertically and laterally spaced on opposite sides of an underground well casing 12, indicated in broken lines, and another pair of jacking cylinders 13 also spaced on opposite sides of the casing, and extending vertically underground. The various cylinders may be supported on concrete as indicated at 14, or merely by the formation itself where the structure thereof is sufficient to support the loads involved. Also, the cylinders are interconnected by a steel ring shown at 15 below the ground surface level 16, the ring preferably being connected to the casing 12 so that jacking and balance loads may be transferred from the pistons and cylinders to the casing.

The lower ends of all the cylinders 11 and 13 are

closed as by means of steel plugs 17, while their upper ends are internally threaded for receiving cylinder heads 18 projecting above the ground level 16. The top surfaces of the heads serve to stop downward travel of enlarged piston rods 19, the lower and relatively smaller end portions 20 of which are secured within tubular balance pistons 21 and jacking pistons 22, these latter being guided for up and down reciprocation by the cylinder heads 18. Suitable packing material 23 seals off between the pistons 21 and 22 and the cylinder heads so as to maintain hydraulic pressure within the spaces between the pistons and the cylinders during their reciprocation.

The extensions 19 of the jacking and balance pistons projecting above ground surface level 16 are interconnected by a cross head structure 25 shown in Figs. 1 and 2 and including transversely extending arms 26 interconnecting the opposite extensions 19 and extending over the well head 27 and supporting a central pump rod 28, which is received downward within the casing 12. A suitable interconnection between the cross head 25 and rod 28 may be a conventional keeper indicated at 29 into which a locking bolt 30 is threaded for securing the keeper to the rod 28.

Speaking generally with respect to flow of fluid and liquid to and from the jacking and balance cylinders, Figs. 1 and 2 show that hydraulic fluid is conducted to and from jacking cylinders 13 via lines 33 branching from common line 34, while liquid under pressure is conducted to and from the balance cylinders via conduits 35 branching from a common conduit 36, both the lines and the conduits described opening into the cylinders underground. While reference in different portions of this description will be made to hydraulic fluid and also to hydraulic liquid, it will be understood that these terms refer to a common hydraulic liquid or fluid, the distinction in terminology being merely for purposes of clarification as regards association of "liquid" with pressure communication to the balance pistons, and "fluid" as concerns pressure communication to the jacking pistons.

Further in this respect, the common source of the hydraulic liquid or fluid is in the bottom portion 37 of a reservoir tank 38, and its upper level upon which gas pressure in the reservoir is exerted fluctuates between the broken lines indicated at 39 and 40 in Fig. 1, associated with the extreme downstroke and upstroke positions of the pistons respectively. Gas pressure in the reservoir is constantly communicated to the balance pistons via the liquid in the bottom portion 37 of the reservoir, and the liquid in the conduits 41, 36 and 35, conduit 41 shown in broken lines in Fig. 1 opening into the bottom portion of the reservoir. It will be understood that this balance pressure exerted on the pistons 11 and tending to raise them together with the pumping rod is insufficient to accomplish such lifting to a degree which may be overcome by the application of hydraulic fluid pressure to the jacking pistons 13, as will be described, the total pressure then being sufficient to lift the pump rod and the string attached thereto in the well. However, upon interruption of hydraulic fluid pressure communication to the jacking pistons, the pump rod 28 and the supporting pistons will drop, such lowering being interrupted before the piston extensions 19 strike the cylinder heads 18.

The above described rather small pressure differential needed to effect raising of the well pump rod and supporting pistons is supplied by the pump 42 shown in Figs. 1 and 2 having its pressure fluid discharge 43 connected through a master valve 44 with lines 33 leading to the jacking pistons during the upstroke, and having its inlet 45 in fluid pressure receiving communication with jacking cylinders via lines 33, 34 and the master valve 44 during the downstroke movement of the pistons and pump rod. Briefly, in regard to the latter condition and

before a description of the master valve is undertaken, it will be observed that, according to Fig. 2, during downstroke of the jacking pistons, hydraulic fluid flows under pressure exerted by the pump rod load to the pump intake at 45, through the pump and then through line 46 and T 47 into the conduit 36 communicating with balance pressure in the reservoir 38. A gear type pump 42 is preferably used to meter fluid backflow from the jacking cylinders to the reservoir during the piston downstroke, the constant speed pump regulating the downstroke speed so that the latter is constant regardless of pressure or vacuum conditions of fluid under the jack pistons and hence at the pump inlet.

Coming now to a description of the master valve 44 referred to in connection with Figs. 1 and 2, it is shown in detail in Fig. 4 to comprise an elongated housing 48 having a bore 49. The latter receives a pair of like plugs 50, preferably cast iron, received endwise oppositely in the bore, the plugs having flanges 51 connected with housing flanges 52 by means of bolts 53. The plugs in turn contain axially aligned bores 54 receiving an elongated valve spool assembly 55 which includes an axial shaft 56 mounting spools or pistons 57 at opposite ends of the shafts, and intermediate spools or pistons 58, the entire spool assembly being shown in its extreme leftward position in Fig. 4. Leftward and rightward travel of the assembly is effected by the alternate introduction of fluid under pressure from ducts 59 and 60.

In the position of the valve spool shown in Fig. 4 hydraulic fluid from the pump 42 flows via pump discharge 43 into the master valve and between the spaced ends of the plugs 50. From there the fluid flows outward through line 34 connected into the master valve housing, the spools 58 confining the flow within the housing to have this described direction during application or communication of fluid pressure to the jacking pistons for lifting the pump rod. At this time, hydraulic liquid from the reservoir enters the master valve through line 46 connected into the housing 48 and discharges at 61, as indicated by the broken lines in Fig. 4, for circulation to the pump intake 45. Therefore, the pressure exerted on the pump intake during the upstroke of the pistons is the pressure existent in the balance cylinders, and may be conveniently referred to as the balance pressure. As a result, the pump adds to the balance pressure its characteristic pressure differential for communication to the jacking pistons for lifting purposes. During this time, the exhaust outlet 62 from the master valve is plugged off from communication with either line 34 or 46.

On the other hand, when the valve spool assembly is at its extreme rightward position as indicated by the broken lines in Fig. 4, hydraulic fluid from the jacking cylinders backflows through line 34 into the master valve unit 55 and discharges at 62 to the pump intake at 45, while the pump discharge 43 is then placed in communication with line 46 and fluid from the pump then flows to the reservoir 38. Under these conditions, the discharge 61 is plugged off from communication with lines 34 and 46.

Further in connection with the construction of the plugs 50, their outside diameters are annularly reduced opposite lines 34 and 46, in the discharges 61 and 62, and the thus formed thin walls of the cylindrical plugs are perforated as shown in Fig. 4, to pass hydraulic fluid back and forth.

Another pair of lines 63 and 64 are connected into the master valve housing 48 opposite lines 34 and 46 to receive hydraulic pressure from the jacking cylinders and from the reservoir respectively. These lines are shown in Fig. 5 as extending to a pressure comparing mechanism generally indicated at 65, which is enlarged in Fig. 6 and shown in detail. The mechanism includes tubular housing 66 receiving end plugs 67 between which a piston 68 is slidable in the housing bore 69. An oppositely endwise extending pair of rods 70 and 71 con-

tected with the piston 68 are guided with endwise reciprocation by plugs 67, rightward travel of the rods being opposed by exertion of hydraulic fluid pressure entering the mechanism from line 63, and leftward travel being opposed by hydraulic pressure from the reservoir conducted via line 64 to the leftward face of the piston 68. Since the balance pressure communicated to the balance pistons is in general less than the hydraulic fluid pressure associated with the jacking pistons during downstroke of the pump rod, resultant pressure differential exerted on piston 68 would tend to move it leftward, were it not for the provision of a suitable compression spring, not shown, within the regulating valve generally indicated at 72. However, when the pressure differential rises beyond a predetermined amount, as for example where the load exerted by the pump rod-carried equipment increases above a certain amount, piston 68 travels to the left and the stepped rod 70 actuates the regulating valve lever 73 to the broken line position shown in Fig. 5. Under these conditions, compressed gas supplied from the tank via line 74 to the regulating valve 72, and then normally via line 75 to a clutch indicated at 76, is bled off at 77 allowing the clutch to engage. Consequently, the motor 78 which is always running then drives the compressor 79 through a V-belt 80 engaged by the clutch, and additional gas is compressed into the tank. Clutch 76 may normally have a spring acting to urge a movable sheave toward the V-belt 80 for engaging same, and a movable piston urging the sheave away from the V-belt under the influence of compressed gas from line 75.

On the other hand, should the hydraulic fluid pressure from the jacking cylinders and communicated to the mechanism 65 via line 63 drop below a predetermined level, the pressure from the tank exerted against the left face of piston 68 plus the action of the spring in the regulating valve 72 will displace the piston 68 and rod 71 to the right, and the latter will actuate a bleeder valve 81, for bleeding excess gas pressure in the tank or reservoir from the valve 81 via line 82. Therefore, the desired pressure differential will tend to be maintained as respects the relationship between the balance pressure and the hydraulic fluid pressure associated with the balance and jacking pistons respectively.

Turning back to Fig. 4, leftward and rightward travel of the valve spool 55 is under the control of a pilot valve indicated generally at 83, and including elongated housing 84 containing a bore 85 in which another valve spool assembly 86 is axially endwise reciprocable. The latter includes a pair of pistons 87 at opposite ends of the spool shaft 88 and a pair of intermediate and spaced pistons 89 which are axially endwise movable between bores 90 in which they are shown as received, and bores 91. In the position shown, hydraulic fluid pressure from the pump discharge at 43 enters the housing 84 via line 92 and flows between the spools 89 and outward via line 59 to the master valve for urging its spool assembly 55 leftwardly to the position in which it is shown. During such leftward travel, hydraulic fluid from line 60 flows back to the pilot valve and then out discharge 93 as shown by the broken lines, through a hand operated valve 94 and to discharge line 95 communicating with the pump discharge. Valve 94 may be opened or closed to the degree as desired for restricting backward flow of fluid through the pilot valve and thereby controlling the rate at which the valve spool 55 travels in the master valve assembly, in turn controlling the stroke of the pump rod 28.

In like manner, when the pilot valve spools 89 are in their alternate position received within bores 91, fluid from the pump discharge at 43 flows into the pilot valve through line 92 and out through line 60 to the master valve for urging valve spool 55 rightwardly. At this time, fluid backflows through line 59 to the pilot valve and out through discharge 96, through a hand operated

valve 97 and to the discharge 95. As above, valve 97 may be adjusted in relation to valve 94 to control the upward travel limit of the pump rod.

Shifting of the pilot valve spool 86 in response to reciprocation of the balance piston 21 shown in Fig. 3 is accomplished by operation of the actuating mechanism generally shown at 98 to include a vertically extending rod 99 reciprocable up and down by the piston extension 19 to which the rod is connected by link 100. The upper end of the rod extends through a sleeve 101 carried by the transverse link 100, and a set screw 102 threaded in the sleeve and engaging the rod, is adjustable to permit control of the rod position relative to the piston extension 19 for changing the stroke length of the pistons and the pump rod 28.

Actuating rod 99 is movable in a vertically extending protective underground tube 103 extending downward from connecting ring 15 supporting cylinder 104 through which the rod 99 projects upward and above ground surface level 16. As better shown in Fig. 4, housing 104 contains a cylinder 116 and a piston 105 reciprocable up and down in the cylinder bore 106, with cylinder end plugs 107 guiding the upper and lower piston extensions 108 and 109 projecting through the plugs. Both the piston and its extensions are tubular so that the rod 99 may reciprocate axially therethrough, suitable O-ring seals 110 and 111 being provided to seal off between the piston 105 and bore 106, and between the piston extensions and the end plugs 107, all for the purposes of retaining hydraulic fluid within the bore spaces 112 and 113 above and below the piston itself. The fluid in spaces 112 and 113 communicates respectively with the pilot valve end spools 87 via lines 114 and 115, so that the pilot valve spool assembly is displaced endwise in accordance with a change in the direction of travel of piston 105.

Housing 104 contains hydraulic fluid standing at a level above check valve intakes 117 to extensions 118 and 119 of lines 114 and 115 respectively within the housing 104, it being understood that liquid may be drawn into those extensions and into the bore spaces 112 and 113 when suction pressures exist therein. Also, suitable ball check pressure relief valves 120 are connected into the fittings 121 and 122 joined to the cylinder 116 and through which fluid in lines 114 and 115 communicates with the bore spaces 112 and 113 respectively. Thus, should the pressure developed by displacement of piston 105 exceed a predetermined level, hydraulic fluid will escape into the fluid chamber 123 in housing 104.

Referring to the operation of the actuating mechanism indicated at 98 in Fig. 3, it will be seen that upward displacement of the actuating rod 99 by the balance piston extension 19 will bring a shoulder 124 at the lower end of rod 99 into engagement with lower end of piston extension 109, and further upward travel of rod 99 will displace piston 105 upwardly in bore 106, effecting a shifting of the pilot valve spool assembly 86 from the position shown in Fig. 4 to its alternate position. Conversely, downward travel of the balance piston extension 19 will cause link 100 to engage the upper end of the piston extension 108, thereby displacing piston 105 downwardly in bore 106 and effecting shifting of the pilot valve spool assembly 86 to the position shown in Fig. 4.

Operation

A complete cycle of operation of the pump jacking apparatus will now be described. At the completion of the pump rod downstroke and at the beginning of its upstroke, the pilot valve and master valve spools 86 and 55 are in the position shown in Fig. 4, facilitating direct communication of hydraulic fluid pressure from the pump discharge 43 to the jacking pistons 22, via lines 33 and 34, the spaces between the jacking cylinders 13 and the pistons 21, and the clearances between the cylinders of the jacking piston heads 32. At this time, fluid stands at level 39 in the reservoir tank 38 as shown in

Fig. 1, and during the jacking piston and pump rod upstroke, fluid flows from the reservoir to the pump intake 45 via the master valve, as explained above. The pump is driven by the motor 78, as by the V-belt drive shown in Figs. 1 and 5, preferably at constant speed, so that the pump rod 28 is steadily lifted, and the liquid level in the reservoir tank 38 falls to the broken line level indicated at 40.

Near the completion of the pump rod upstroke, the actuating rod 99 effects the lifting of the piston 105, with consequent shifting of the pilot valve and master valve spool assemblies 86 and 55. This time, hydraulic fluid in the jacking cylinders is placed in communication with the pump intake 45 via the master valve, as explained above, and the pump discharge 43 is connected with the fluid in the reservoir 38, also via the master valve and lines 46 and 36 as shown in Fig. 2. Therefore, the only hydraulic liquid pressure tending to lift the pump rod 28 is the balance pressure exerted on the balance piston head 31, so that the pump and rod begins its downstroke, together with the jacking and balance pistons. During such downstroke, the pump 42 driven at constant speed brakes the downward travel of the jacking pistons since hydraulic fluid under pressure exerted by those pistons can flow through the pump only as regulated by the pump speed. Therefore, the pump meters or restricts hydraulic fluid flow toward the reservoir 38, and the level of fluid in the reservoir rises at a constant rate in accordance with such metering to the upper level 39 at the completion of the downstroke.

Oil standing in the lower section of the reservoir is conveniently cooled by air blown between the outer and inner shells 130 and 131 by means of a fan 132 rotated by pump shaft extension 133 in the inlet 134, as indicated in Fig. 7. After passing in cooling relation to the oil standing within the inner shell 131 of the reservoir, air flows through the outlet 135.

Reference to Fig. 1 shows the pump 42, reservoir tank, compressor, and valves 43 and 44 mounted on a frame 137 standing on the ground, whereas the actual jacking cylinders and pistons extend well below ground level. It is of course understood that the reservoir tank 38 may be mounted horizontally to decrease the height of the equipment standing above ground.

I claim:

1. An apparatus for vertically reciprocating a loaded rod at a constant uniform rate on the downstroke thereof irrespective of variation of the magnitude of said load on said rod which includes: a plurality of substantially vertically extending and laterally spaced cylinders adjacently disposed to said rod; piston means reciprocal up and down in said cylinders; a reservoir partially filled with hydraulic fluid and having a quantity of gas at at least a predetermined minimum second pressure situated thereabove; a source of gas at a pressure substantially higher than said second pressure; a positive displacement pump; a prime mover which when operating continuously drives said pump; first valve means which include a movable valve member capable of occupying first and second positions; first conduit means which when said valve member is in said first position have said fluid flowing therethrough from said reservoir to the suction of said pump to be discharged to a first portion of said cylinders at a first pressure higher than said second pressure to cause said pistons therein to rise and raise said loaded rod; second conduit means which when said valve member is in said second position and said loaded rod moves downwardly from the top of its stroke have said hydraulic fluid flowing therethrough from said first cylinders to the suction of said pump, and the discharge of said pump being conducted by said second means to said reservoir, with the rate at which said fluid is pumped through said pump solely determining the rate at which said loaded rod moves downwardly on the downstroke thereof; means responsive to the movement

of said loaded rod that move said valve member to said first position at substantially the termination of the downstroke of said rod and to said second position at substantially the completion of the upstroke by said rod; 5 third conduit means extending between said reservoir and said second portions of said cylinders to force said pistons therein by fluid at said second pressure to support a predetermined fraction of said load on said rod on both the upstroke and downstroke thereof; and means 10 sensitive to the pressure of said gas in said reservoir and said fluid at said first pressure that bleeds gas from said reservoir, or admits gas from said source to said reservoir to automatically maintain a predetermined differential in pressure that is substantially constant between said first and second pressures to force said pistons in said second portions of cylinders to support said predetermined fraction of said load on said rod on both the upstroke and downstroke thereof, even if the magnitude of said load over a period of time varies.

2. An apparatus as defined in claim 1 in which said source of gas under pressure is a gas compressor, and an air pressure controlled clutch is provided capable of driving said compressor together with transmission means connecting said clutch to said prime mover, and 25 the air pressure on said clutch varied to place said clutch in a compressor driving position to supply gas to said reservoir until the pressure of said gas in said reservoir has risen sufficiently to establish said predetermined differential between said first and second pressures by operation of said means sensitive to said gas pressure in said reservoir and said fluid in said first portion of cylinders.

3. An apparatus as defined in claim 1 in which said valve means includes a hollow enclosed body having first, second, third, fourth, fifth and sixth fluid passages formed therein, and said first conduit means includes a first conduit connected to the discharge of said pump and said first passage, a second conduit connected to the interior of said reservoir and said second passage, a third 35 conduit connected to the suction of said pump and said third passage, a fourth conduit connected to said fourth passage and the interior of said first portions of said cylinders, with said member disposed in said body, and when said member is occupying said first position establishing communication between said first and fourth passages and said second and third passages, and said fifth and sixth passages connected to said second conduit means.

4. An apparatus as defined in claim 3 in which said second conduit means includes a fifth conduit connected to said fifth passage and said suction of said pump, a sixth conduit connected to said sixth passage and the interior of said reservoir, and said member in said valve when in said second position establishing communication between said fourth and fifth passages and said first and sixth passages.

5. An apparatus as defined in claim 3 in which movement of said valve member in said valve body is in response to hydraulic fluid pressure exerted thereon, and 60 a pilot valve is provided that controls hydraulic fluid under pressure that is caused to be exerted on said valve member in response to reciprocation of said loaded rod.

6. An apparatus as defined in claim 3 in which said means responsive to the second pressure of said gas in said reservoir and the first pressure of said fluid in said first portion of said cylinders is a hollow cylindrical body in which a piston is slidably mounted which has two piston rods extending outwardly from opposite sides thereof through said body, the end interior portions of said body in communication with said gas in said reservoir and said fluid in said first portion of said cylinders, with a normally closed bleed-off valve being provided that is in communication with said gas in said reservoir, and said piston when said pressure of said gas in said reservoir attains more than a predetermined

differential relative to said fluid at said first pressure moving in a direction to cause one of said piston rods to actuate said bleed-off valve to assume an open position until sufficient of said gas in said reservoir has escaped through said bleed-off valve to permit said piston in said body to move out of said position in which said bleed-off valve is actuated.

7. An apparatus as defined in claim 6 in which a valve is provided that controls the air supply to said clutch, and said piston in said body when said gas pressure in said reservoir falls below said differential relative to said pressure on said fluid in said first portion of cylinders, moving in a direction to cause one of said rods projecting from said piston to actuate said air control valve until said air pressure in said reservoir has built up to said predetermined differential relative to said pressure of said fluid in said first portion of cylinders.

8. In a hydraulically operated unit to reciprocate a substantially vertically disposed loaded rod of the type of unit which includes a first cylinder with a first piston movably disposed therein that raises said rod when a hydraulic fluid under pressure is discharged into said first cylinder, a second cylinder and second piston movably disposed therein, which second piston partially supports said load on said rod on each upstroke and downstroke thereof when hydraulic fluid under pressure is maintained in said second cylinder, said first and second pistons being rigidly connected to said rod, the improvement in which the downward movement of said rod is maintained at a desired uniform rate irrespective of variation in the load on said rod comprising: a positive displacement pump capable of discharging hydraulic fluid under pressure when actuated; a prime mover that actuates said pump at a constant pumping rate; a reservoir of sufficient volume to hold a quantity of said hydraulic fluid greater than that required to be discharged into said first cylinder to raise said piston and rod on said upstroke a predetermined distance and to cause said second piston at all times to partially support said load on said rod; first valve means that includes a body having first, second, third, fourth, fifth and sixth fluid passages formed therein, and a valve member movably mounted in said body, said valve member capable of occupying a first position in which said first and fourth passages are in communication as are said second and third passages, and a second position in which said fourth and fifth passages are in communication as are said first and sixth passages; a first conduit connected to the discharge of said pump and said first passage; a second conduit connected to the interior of said reservoir and said second passage; a third conduit connected to said third passage and the suction of said pump; a fourth conduit connected to said fourth passage and the interior of said first cylinder; a fifth conduit connected to said fifth passage and said suction of said pump; a sixth conduit connected to said sixth passage and the interior of said reservoir; a seventh conduit connected to the interior of said reservoir and said second piston; means that at all times maintain at least a predetermined minimum pressure on said fluid in said reservoir to exert an upward force on said second piston at all times to partially support said load on said rod; means responsive to the movement of said rod that moves said valve member to said first position as said first piston approaches the completion of its downstroke and to said second position upon said rod being raised on the upstroke thereof to a predetermined elevation, said valve member in said first position permitting

said pump to draw said fluid from said reservoir through said second and third conduits from said reservoir under a head of at least said minimum pressure and discharge said hydraulic fluid through said first and fourth conduits to said first cylinder to raise said rod to said predetermined elevation, with said valve member in said second position permitting the portion of said load on said rod not supported by said second piston to move said rod downwardly with concurrent discharge of said fluid from said first cylinder through said fourth and fifth conduits to the suction of said pump to be discharged therefrom through said first and sixth conduits to the interior of said reservoir, and said pump when discharging said fluid through said first and sixth conduits acting as a regulator to control the rate at which said rod moves on said downstroke thereof.

9. In a hydraulically operated unit as defined in claim 8 in which said means to maintain said substantially constant head on said fluid in said reservoir is a quantity of a gas disposed therein that is at all times maintained above the predetermined pressure required for said second piston to support said desired portion of said load on said rod on both the upstroke and downstroke thereof.

10. In a hydraulic pumping unit as defined in claim 9 in which a desired differential is automatically maintained between the pressure on said fluid in said first cylinder and said pressure on said gas in said reservoir by providing a source of said gas at a pressure substantially greater than said minimum pressure, a normally closed gas bleed off valve on said reservoir, means which when actuated result in the flow of said gas from said source to said reservoir, and a pressure-comparing mechanism including a movable member, said mechanism at all times in communication with said gas in said reservoir and said fluid in said first cylinder, said member responsive to a predetermined differential in pressure between the pressure on said fluid in said first cylinder and the pressure on said gas in said reservoir, said member being moved to a first position when the pressure on said fluid in said first cylinder exceeds said predetermined differential relative to said gas in said reservoir, said member in said first position actuating said means to permit flow of said gas to said reservoir, said member being moved to a second position when the pressure on said gas in said reservoir exceeds said predetermined differential relative to said pressure of said fluid in said first cylinder, said member when in said second position maintaining said bleed-off valve in an open position to permit discharge of said gas to the ambient atmosphere until the difference in pressures between said gas in said reservoir and said fluid in said first cylinder is at said predetermined differential.
